UNITED STATES PATENT OFFICE.

PIETRO CARDARELLI AND AURELIO MERCIERI, OF UTICA, NEW YORK.

RAIL-JOINT.

1,095,809.

Specification of Letters Patent.

Patented May 5, 1914.

Application filed December 31, 1913. Serial No. 309,780.

To all whom it may concern:

Be it known that we, PIETRO CARDARELLI and AURELIO MERCIERI, subjects of the King of Italy, residing at Utica, in the county of 5 Oneida and State of New York, have invented new and useful Improvements in Rail-Joints, of which the following is a specification.

The present invention relates to rail joints, and the primary object of the same is to provide a rail joint whereby the rails may be easily and securely connected and further whereby neither of the rails will be restricted in its longitudinal movement incident to the expansion and contraction of 15 the rails due to temperature changes.

A further object of the invention is to provide rails having lapping ends with fish plates for connecting the ends and to arrange the said fish plates so that the rails may contract or expand without influencing the connecting plates.

With the above and other objects in view, the invention consists in the construction, 25 combination and arrangement of parts set forth in the following specification and falling within the scope of the appended claim.

In the drawing: Figure 1 is a side elevation of two rails constructed in accordance 30 with the present invention. Fig. 2 is a horizontal sectional view on the line 2—2 of Fig. 1, and Fig. 3 is a transverse sectional view on the line 3—3 of Fig. 1. Fig. 4 is a detail perspective view of the bolt.

In the drawings, the rails are indicated by the characters R—R' and the body of each of said rails is of the ordinary construction. Each of the rails, at its ends, and upon one of its sides, is provided with 35 integrally formed extensions in the nature of plates 1—1'. The plates have their inner faces arranged in a line with one of the sides of the web of each of the rails, and are of a width equaling the distance between 40 the head and base flange of the rail, while the edges of the plates conform to the shape of the upper faces of the base flanges of the rails.

The vertical plate upon the rail R is 45 designated by the numeral 2, and the vertical plate projecting beyond the end of the rail R' is indicated by the numeral 3. The webs of the said rails are enlarged or thickened for a considerable distance from their 50 ends proper, and these enlarged or thickened portions, which may be designated by the

numerals 4 and 5 respectively are formed with transversely arranged elongated openings 6 and 7 respectively, two of the openings 6 being provided in the rail R, and a 60 similar number being provided in the enlarged portion of the rail R'. The plates 2 and 3 are also provided with elongated openings 8 and 9 respectively, corresponding in number and size with the openings 6 and 7, and these openings are adapted to align when the rail ends abut. Upon the enlarged portion and plate 2 of the rail R we employ two bars or plates 10 and 11 respectively, each of the plates being provided 65 with a pair of round openings 12 and 13. These openings are adapted to communicate centrally with the elongated openings above mentioned, and upon the outer face of the plate 3 and the enlarged portion of the rail 70 R', we provide two similar plates 14. These plates are each provided with a pair of elongated openings 16 and 17 respectively. The openings 16 and 17 may be of a length 75 corresponding with the length of the elongated openings in the rails and their angular extensions or may be of a lesser width if desired. The openings 16 and 17 are adapted to snugly receive the locking shoulders 80 18 which are arranged upon the heads 19 of bolts 20. The shoulders do not extend through the openings 16 and 17, that is, they do not project to within the elongated openings formed in the enlarged portions of the shoulders and the vertical extensions of the 85 angle members of the rails, so that only the rounded shanks of the said bolts pass through the elongated openings and through the round openings 12 and 13 in the plates 10 and 11. Nuts 21 are employed upon the 90 extending ends of the bolts. The nuts only bind sufficiently against the plates 10 and 11 to hold the joint against lateral movement, while a free longitudinal movement, 95 incident to the expansion and contraction 100 of the rails is permitted.

By our arrangement it will be noted that no dirt or other undesirable matter may enter the elongated openings in the rail ends to retard the same against their longitudinal movement incident to expansion or contraction. This is a feature greatly desired, as disasters have resulted from the breakage of the rails at the joints because no provision was made for the free expansion and contraction of the rails at this 105 point, and further, for the reason that for

esign matter has been permitted to enter the bolt openings which serves as an obstruction or as a means for halting the longitudinal movement of the rails ends, and as a consequence, causing the breakage of the rails at the joints. It will also be noted that the arrangement of the plates is such as to permit of the rail ends moving longitudinally from or toward each other without 10 engaging the plates.

From the above description, taken in connection with the accompanying drawings, the simplicity of the device as well as the advantages thereof will, it is thought, be 15 perfectly apparent to those skilled in the art to which such inventions appertain without further detailed description.

Having thus described the invention, what we claim is:

20 The combination with two rails having lapped ends and provided with elongated bolt openings, plates arranged in pairs on

the opposite sides of the rails and at the ends thereof, the plates on one side of the rails having elongated openings corresponding to and registering with the elongated openings in the rail ends, the plates on the opposite sides of the rails having round openings which are arranged centrally of the elongated openings in the rail ends, 25 shouldered bolts passing through the openings, the said bolts having their shoulders engaged with the walls in the elongated openings in the first mentioned pair of plates and having their shanks engaging 30 with the elongated openings in the second pair of plates, and nuts for the bolts.

In testimony whereof we affix our signatures in presence of two witnesses.

PIETRO CARDARELLI.
AURELIO MERCIERI.
